UNITED STATES PATENT OFFICE.

CHARLES E. WARD, OF CHARLESTON, WEST VIRGINIA.

LIQUID HEATER AND VAPORIZER.

Application filed March 14, 1921. Serial No. 452,044.

To all whom it may concern:

Be it known that I, CHARLES E. WARD, a citizen of the United States, residing at Charleston, in the county of Kanawha and State of West Virginia, have invented certain new and useful Improvements in Liquid Heaters and Vaporizers; and I do hereby declare the following to be a full, clear, and exact description of the invention, such as will enable others skilled in the art to which it appertains to make and use the same.

This invention relates to liquid heaters and vaporizers and more particularly to the so-called "express" type of boiler and superheaters therefor, and has for its object to provide such a boiler and superheater which will be comparatively simple in construction and more efficient in action than those which have been heretofore proposed.

With these and other objects in view, the invention consists in the novel details of construction and combination of parts more fully hereinafter disclosed and particularly pointed out in the claims.

Referring to the accompanying drawings forming a part of this specification, in which like numerals designate like parts in all the views:

Figure 1 is a vertical, transverse sectional view of a portion of an "express" type of steam boiler and superheater therefor, made in accordance with the present invention;

Figure 2 is an enlarged diagrammatic horizontal sectional view taken approximately on the line 2-2 of Figure 1, looking in the direction of the arrows;

Figure 3 is a view similar to Figure 2, but taken on the line 3-3 of Fig. 1, looking in the direction of the arrows;

Figure 4 is a view similar to Fig. 1, of a slightly modified form of the invention; and

Figure 5 is a vertical sectional view taken approximately on the line 5-5 of Figure 4.

In the prior United States Patent No. 1,318,059, granted October 7, 1919, to Charles W. Dyson, there is disclosed an "express" type of steam boiler and superheater therefor, wherein the superheater tubes are adapted to enter and normally occupy positions in lanes formed in the steam generating tubes by the omission of a portion of such generating tubes. It is pro-

posed in this said Dyson patent to mount the lower superheater drum approximately in the same horizontal plane as the lower generating drum of the boiler and to one side thereof, and it is further proposed to so mount this lower superheater drum as to be able to rotate the same, thereby permitting the entire superheater to be swung about the axis of the said lower superheater drum, so that the superheater tubes may be withdrawn from the lanes formed in the steam generating tubes, whereby ready access may be had to the said superheater tubes for repairs, etc.

It has been found in actual practice, however, that when boilers of this type are designed for use aboard ships, and especially aboard war vessels, where the factor of space occupied by the boiler is an exceedingly important one, that the mounting of the lower superheater drums in the same horizontal plane as the lower boiler drums and to one side thereof, causes the boiler and superheater to assume such lateral dimensions as to be prohibitive.

It is therefore one of the objects of the present invention to so arrange the superheater drums and tubes so as to reduce the lateral space required to little, if any, more than that normally required for the boiler alone.

Referring now to Figs. 1, 2 and 3 of the drawings:

1 indicates a water tube boiler of the so-called "express" type, provided with a relatively large upper drum 2 and with the usual lower drums 3, only one of which is shown in the drawings, it being understood, however, that all the parts illustrated in Figure 1 are, or may be, duplicated exactly, in a reversed relation, upon the left hand side as seen in said figure. The said drum 2 is perforated in the usual manner to receive the upper ends of a set of water tubes 4, the lower ends of which are suitably introduced into the lower drum 3, as indicated.

5 designates generally the superheater comprising a lower drum or receptacle 6, an upper drum or receptacle 7, and a series of connecting tubes 8, the ends of which are respectively introduced into the said drums 6 and 7, as will be readily understood. The said drums 2, 3, 6, and 7 may be suitably supported in any desired manner upon the furnace structure 18, which

structure of course, includes a fire box 9 the efficiency of the lower portion of the steam generating tubes adjacent the lanes will be lost.

In order to carry out the primary object 5 of the invention, and to reduce the lateral dimensions of the boiler and superheater, instead of mounting the lower superheater drums 6 in the same horizontal plane as the lower boiler drum 3, and to one side 10 thereof, as was the case in the above mentioned prior Patent #1,318,059, I have raised the drum 6 until it occupies substantially the same vertical plane as the drum 3.

As will be readily apparent, this is possible, 15 due to the fact that the steam generating tubes 4 are sharply inclined in this type of boiler so that by raising the drum 6 into a horizontal plane above that of the drum 3 it is possible to move the said drum 6 inwardly to approximately the same vertical plane as the said drum 3.

As best shown in Figures 2, and 3, the steam generating tubes 4 connecting the drums 2 and 3 are arranged to provide open 25 lanes or pasages 10, this being accomplished by the omission of a portion of certain of the rows of steam generating tubes, all as was clearly pointed out in the said Dyson patent.

30 In like manner the superheater tubes 8 are arranged in rows such as 11, adapted to enter the said lanes 10 and occupy a portion of the length of the same. Due to the fact, however, that the lower superheater drum 35 6 has been moved upwardly and inwardly from its position, as shown in the said Dyson patent, the length of the superheater tubes 8 has been greatly decreased, so that in the present construction they occupy only 40 the upper portion of the length of the lanes 10, which are provided in the steam generating tubes. The length of these said superheater tubes, as well as the length of the portion of the lanes which they occupy may 45 be varied more or less to meet specific operating conditions, but as here shown, the said superheater tubes will occupy only approximately say one half of the length of the lanes existing in the steam generating 50 tubes.

Owing to this reduction in the length of the superheating tubes it, of course, results 55 that the lower portion of the lanes formed in the steam generating tubes is unoccupied, and I have found from practical experiments that if this said unoccupied space is permitted to exist, a relatively large proportion of the gaseous products of combustion which pass from the fire box 9 around 60 the tubes 4 and 8 will pass into and through the said unoccupied portions of said lanes instead of around those steam generating tubes which are adjacent thereto. In other words, the said hot gases will follow the 65 path of least resistance and a great deal of

Accordingly, in order to overcome this objection, I propose to fill up the unoccupied lower portions of the lanes 10 in any suitable manner, as for example, by the metallic baffles or filling members 15, constructed in any suitable manner, either of solid or sheet metal material, as illustrated, and adapted to substantially completely occupy the lower portion of the lanes 10 which is not required for the rows 11 of the superheater tubes 8.

It thus results that when the hot gases from the fire box 9, after passing around the left hand steam generating tubes 4, as seen in the drawings, arrive at the lower portions of the lanes 10 existing between the said tubes, instead of being able to pass directly through the said lanes and thus escape contact, to a large degree, with the generating tubes 4 adjacent the said lanes, they will be forced to pursue a zig-zag path between the said adjacent tubes, thereby greatly increasing the efficiency of the lower portions of said tubes. On the other hand, such of the gases as pass across the upper portion of the steam generating tubes above the baffle members 15 and into the upper portions of the lanes 10 will be brought into contact with the superheater tubes 8, whereby by the heat carried by the said gases will be extracted therefrom by the said superheater tubes in the usual manner.

100 In order to facilitate the conservation of the heat energy contained in the hot gases, I also prefer to provide a horizontal baffle member 17 running substantially the entire length of the boiler and in close proximity to the lowermost superheater tube substantially 105 as shown. This baffle member 17 likewise tends to cause the hot gases to remain longer in contact with the various steam generating and superheating tubes, and therefore serves to increase the total efficiency of the boiler. 110

The superheater 5 in the preferred form of the present invention may be mounted similarly to that disclosed in the said Dyson patent above. That is, the lower drum 6 may be so mounted as to be capable of rotation about its longitudinal axis so that the entire superheater may be swung outwardly around the axis of the drum 6 should it become necessary to repair or to renew any of the superheater tubes.

115 It will, of course, be understood that a baffle member 15 is provided for the lower portion of the length of each of the lanes formed in the steam generating tubes 4 and these said baffle members may be constructed individually and secured in any suitable manner to the furnace structure or wall 18, or a plurality of them may be secured together and suitably supported from the ends of the furnace or in any other desired manner.

In the somewhat modified form of the invention shown in Figs. 4 and 5, instead of providing solid or sheet metal baffles or filling members for the lower portions of the lanes in the steam generating tubes, I have shown what is substantially a water baffle for these said lanes. That is to say, instead of providing a lower superheater drum such as 6, I substitute therefor two receptacles or chambers 22 and 23, as will be clear from Fig. 4. The lower ends of the superheater tubes 8 are introduced through the wall of the chamber 22, which, as will be readily apparent, takes the place of the superheater drum 6 above described. The chamber 23 is rigidly secured in any suitable manner to the furnace structure 18, while the chamber 22 is hinged to the said chamber 23, as at 21, thereby permitting the chamber 22 to be oscillated in much the same manner as the drum 6.

Leading from the chamber 23 is a plurality of rows of water tubes 24 which tubes are introduced through the wall of the said chamber in vertical alinement with the rows 11 of the superheater tubes, so that the said tubes 24 are disposed in rows similar to the said superheater tubes, and are adapted to enter and occupy the lower portions of the lanes 10 in the steam generating tubes. The lower ends of these said tubes 24 may be introduced into the lower water drum 3 in the same manner as the generating tubes 4, as will be readily apparent. Suitable 30 turn or relief pipes 25 may connect the chamber 23 with the steam drum 2, substantially as shown, these said pipes being disposed intermediate of the rows of tubes 24, and also of the rows of tubes 11, of the superheater, and running upwardly outside of the steam generating tubes, as will be clear from Figure 4.

It will therefore be seen that in this form of construction substantially the same result is accomplished, in that the lower portions of the lanes 10 which are not occupied by the rows 11 of superheater tubes are substantially filled by the rows of water tubes 24, thereby preventing the escape of the hot gases through the lower portions of the said lanes without completely discharging their heat units.

It will thus be seen that by the present construction I have provided an "express" type of boiler and a superheater therefor, wherein the entire width of the boiler and superheater is not increased at all over the lateral dimensions of the boiler alone; that the generating tubes of the said boiler are provided with lanes into which are adapted to enter the rows of superheater tubes in the same manner as was disclosed in the said prior patent to Dyson; that the said superheater may be so constructed and mounted 60 as to be rotatable about the axis of its lower

chamber whereby its tubes may be withdrawn from the lanes formed in the generating tubes, for the purpose of repair or renewal, in exactly the same manner as disclosed in the Dyson patent; and that, owing 70 to the fact that the lower chamber 6 of the superheater has been moved upwardly and inwardly in order to accomplish the desired result of lessening the total lateral dimension of the boiler, the length of the 75 superheater tubes is greatly lessened, leaving unoccupied a portion of the length of the lanes in the steam generating tubes which unoccupied portion is filled in any suitable manner, as by the baffles 15, in order to force 80 the hot gases into more intimate contact with the steam generating tubes adjacent the lower portion of the lanes, thereby conserving the heat carried by said gases and increasing the efficiency of the boiler.

It is obvious that those skilled in the art may vary the details of construction, as well as the arrangement of parts without departing from the spirit of the invention, and therefore, I do not wish to be limited 90 to the above disclosure, except as may be required by the claims.

What I claim is:—

1. In a steam boiler the combination of an upper and a lower drum; a set of steam 95 generating tubes joining said drums inclined to a horizontal plane and so arranged as to provide a plurality of open-ended lanes extending lengthwise of said tubes and transversely of said drums; an upper and a 100 lower superheater receptacle, said lower receptacle being disposed sufficiently above said lower drum as to occupy substantially the same vertical plane as said lower drum; a set of superheater tubes joining said superheater receptacles arranged in a plurality of 105 rows and adapted to enter and occupy a portion only of the length of said lanes; and means adapted to occupy another portion of the length of said lanes and to prevent hot gases from passing therethrough, substantially as described.

2. In a steam boiler the combination of an upper and a lower drum; a set of steam generating tubes joining said drums and so 110 arranged as to provide a plurality of open-ended lanes extending lengthwise of said tubes and transversely of said drums; an upper and a lower superheater drum, said lower superheater drum being disposed substantially in the same vertical plane as said lower boiler drum; a set of superheater tubes joining said superheater drums arranged in a plurality of rows and adapted 115 to enter and occupy a portion of the length of said lanes; and means comprising a plurality of baffles extending transversely of said drums and longitudinally of said superheater tubes adapted to occupy another portion 120 of the length of said lanes and to ex- 125 130

clude hot gases therefrom, substantially as described.

3. In a steam boiler the combination of an upper and lower drum; a set of inclined steam generating tubes joining said drums and so arranged as to provide a plurality of open ended lanes extending lengthwise of said tubes; an upper and lower superheater receptacle; a pivoted means associated with said lower superheater receptacle about which said upper receptacle may oscillate, said pivoted means located above and in substantially the same vertical plane as said lower drum; a set of curved superheater tubes joining said superheater receptacles arranged in a plurality of rows so spaced apart as to be capable of entering and occupying a portion of the length of said lanes; and baffle means extending transversely of said drums and longitudinally of said superheater tubes, adapted to occupy the lower portions of said lanes and to aid in excluding hot gases from said lanes.

4. In a steam boiler the combination of an upper and lower drum; a set of inclined steam generating tubes joining said drums and so arranged as to provide a plurality of open ended lanes extending lengthwise of said tubes; an upper and lower superheater receptacle; a pivoted means associated with said lower superheater receptacle about which said upper receptacle may oscillate, said pivoted means located above and in substantially the same vertical plane as said lower drum; a set of curved superheater tubes joining said superheater receptacles arranged in a plurality of rows so spaced apart as to be capable of entering and occupying a portion of the length of said lanes; a hot water receptacle associated with said lower superheater receptacle; and baffle means joined to said hot water receptacle extending transversely of said drums and longitudinally of said superheater tubes, adapted to occupy the lower portions of said lanes and to aid in excluding hot gases from said lanes.

5. In a liquid heater and vaporizer the combination of an upper and a lower boiler drum; a set of steam generating tubes joining said drums and so arranged as to provide a plurality of open ended lanes extending lengthwise of said tubes; an upper superheater receptacle; a lower superheater receptacle disposed in substantially the same

vertical plane as said lower boiler drum; a pivot associated with said lower receptacle around which said upper receptacle may oscillate; a set of superheater tubes joining said upper superheater receptacle and said lower superheater receptacle arranged in a plurality of rows adapted to enter and occupy a portion only of the length of said lanes; a water receptacle associated with said lower superheater receptacle; and a set of water tubes joining the said water receptacle and said lower boiler drum, said last named tubes arranged in a plurality of rows and adapted to enter and occupy another portion of the length of said lanes, substantially as described.

6. In a liquid heater and vaporizer the combination of an upper and a lower drum; a set of steam generating tubes joining said drums and so arranged as to provide a plurality of open ended lanes extending lengthwise of said tubes; an upper and a lower superheater receptacle, said lower receptacle being disposed in substantially the same vertical plane as said boiler drum; a set of superheater tubes joining said receptacles arranged in a plurality of rows and adapted to enter and occupy a portion of the length of said lanes; and means comprising a plurality of water conducting baffle members adapted to enter and occupy another portion of the length of said lanes, substantially as described.

7. In a liquid heater and vaporizer the combination of an upper and a lower drum; a set of steam generating tubes joining said drums and so arranged as to provide a plurality of open ended lanes extending lengthwise of said tubes; an upper superheater drum; a plurality of chambers disposed in substantially the same vertical plane as said lower boiler drum; a set of superheater tubes joining said superheater drum and one of the chambers arranged in a plurality of rows adapted to enter and occupy a portion only of the length of said lanes; a set of water tubes joining the other of said chambers and said lower boiler drum arranged in a plurality of rows and adapted to enter and occupy another portion of the length of said lanes; and connections between said second chamber and said upper boiler drum, substantially as described.

In testimony whereof I affix my signature.
CHARLES E. WARD.
